HOLD-DOWN BRACKET

Harry H. Nelson, New York, N. Y., assignor to
 Lorentzen Hardware Mfg. Corp., New York,
 N. Y., a corporation of New York

Application September 20, 1944, Serial No. 555,011

11 Claims. (Cl. 160—349)

1

My invention relates to improvements in hold-down brackets for the bottom rail of Venetian blinds, by means of which brackets the pendant blind is restrained against inadvertent lifting, swinging or flapping.

Various forms of hold-down brackets have been used heretofore, but so far as I am aware none of them has possessed all of the characteristics that are commercially desirable. The prior art hold-down brackets have presented one or more of the following difficulties or limitations: specialized problems of installation in or on window and door trim of various types; disfigurement of the window or door with an unsightly accessory which is exposed when the blind is elevated; the tendency of the bracket to snag dusters and wiping cloths employed for cleaning the door or window trim; lack of resistance to bending and distortion under abuse; and the need for providing a plurality of different specific forms of brackets to take care of left and right, jamb and still mounting.

A general object of my invention is to provide a Venetian blind hold-down bracket which obviates all of the foregoing difficulties and limitations.

One particular object of the invention is to provide a hold-down bracket which is susceptible of facile installation.

Another object of my invention is to provide a single bracket which is of "universal" construction, i. e., so constructed that a pair of identical brackets may be installed, one at the left and the other at the right lower corner of the blind area, either upon the jamb or sill of the light opening to be shrouded.

It is a further object of my invention to provide a Venetian blind hold-down bracket which is sightly when fully exposed to view due to elevation of the blind slats.

It is another object of my invention to provide a Venetian blind hold-down bracket which is free from tendency to snag clothing, dusters, wiping cloths, and other objects which may come into contact therewith.

Additional objects of my invention are to provide a hold-down bracket for Venetian blinds which is inherently strong and resistant to bending and buckling under conditions of use and abuse; which is inexpensive to manufacture; which may be fabricated from inexpensive sheet metal by a simple punching and pressing operation, which can be mounted by means of a single screw driven in the window or door trim; and which, for some purposes (such as compensation

2

for stretch in the ladder tapes of the associated blind) affords engagement with the bottom rail of the blind at more than a single level.

Further objects, and objects relating to details and economies of manufacture, installation and use will more definitely appear from the detailed description to follow.

My invention is clearly defined in the appended claims. In the claims, as well as in the description, parts are identified by specific names for convenience, but such nomenclature is intended to be as generic, in its application to similar parts, as the prior art will permit. The best form in which I have contemplated applying my invention is illustrated in the accompanying drawing forming part of this specification, in which:

Figure 1 is a perspective view of a corner of a window casing provided with a hold-down bracket constituting a preferred embodiment of my invention, said bracket being secured to the left jamb of the window casing with a single wood screw;

Figure 2 is an edgewise view, in elevation, of a similar hold-down bracket secured to the sill of a window casing, the bracket being set in somewhat from the corner of the window casing to accommodate a blind of lesser width, and the wood screw being inserted through the foot of the bracket instead of through the body thereof as in Figure 1;

Figure 3 is a view, in side elevation, of the type of bracket illustrated in Figures 1 and 2, but installed on the exterior face of the window casing;

Figure 4 is a side elevational view of the bracket illustrated in perspective in Figure 1;

Figure 5 is an edgewise view of the bracket illustrated in Figure 4, showing the offset braced character of its body portion;

Figure 6 is a top plan view of the said bracket; and

Figure 7 is a fragmentary sectional view taken on the line 7—7 of Figure 5 depicting, on an enlarged scale, the formation of the screw-receptive, non-rotating foot portion thereof.

Similar reference numerals refer to similar parts throughout the several views.

My invention relates to Venetian blinds of the type having a bottom rail or heavy slat on each end of which is mounted an outwardly-extending gudgeon pin. In a broad sense, my invention may be said to find embodiment in a unique bracket to be secured (one at each side of the lower extremity of the blind) upon the adjacent door or window trim and to be engageable, re-

spectively, with the proximate gudgeon pin of the said bottom rail of the blind. The bracket is preferably formed by stamping and pressing from sheet metal and serves as a hook with which the adjacent gudgeon pin may be readily engaged by depressing the bottom rail against the tension of the ladder tapes of the blind. More specifically, the bracket structure is of a form such that a single standardized type may be used at either the right or the left side of the blind. Furthermore, the bracket structure is preferably provided with two mounting portions, one at right angles to the other, so that the bracket may be secured upon either the jamb or the sill of a window or door casing, and may be disposed upstanding thereon or outstanding therefrom. When used in outstanding position, two levels for gudgeon-pin engagement are available, the upper normally being used and the lower, located some $\frac{3}{8}$ " therebelow, being desirable for use when stretch has occurred in the ladder tapes of the blind after long service. In its preferred form, the bracket is approximately of L configuration, the foot serving as a mounting flange receptive of a conventional wood-screw or the like, and the standing portion being punched and pressed to define an inset terminal flange provided with a notch formation for gudgeon-pin reception and retention. The notch formation is preferably double in nature, a notch disposed at each side of the center line of the bracket, and the portion of the inset terminal flange which lies between said notches is extended to constitute a similarly inset stop and pin-guide effective to direct the gudgeon pin into one of said notches which is appropriate to the left or right-hand mounted position of the bracket. The thus-constituted pin stop and guide is formed integral with the standing portion proper of the bracket as well as with the inset flange thereof and thus serves the additional function of a bracket stiffening member. The two notches of the bracket are directed obliquely of its longitudinal axis and diverge so that a gudgeon pin held against the pin stop is guided to enter the appropriate notch with equal facility and security, regardless of whether the bracket be located at the left or right side of the blind, and regardless of whether the bracket be mounted upstandingly or outstandingly.

In Fig. 1 of the accompanying drawing, I have shown (secured to the left jamb A of a conventional window casing) a hold-down bracket effective to restrain the left end gudgeon pin 11 of the bottom rail 10 of a Venetian blind (shown only fragmentarily) against upward and sidewise movement. This bracket is formed by punching and stamping from sheet metal and consists, generally, of a foot portion 13 adapted for abutment with a surface of a window or door casing, and a standing portion 12. The end of the standing portion which is remote from the foot 13 is bent to form a stepped flange 14, which flange is provided with a diverging pair of notches 15 and 16 receptive, selectively, of the proximate gudgeon pin 11 carried by the bottom rail 10 of the blind. By virtue of the inwardly-stepped character of the thus-notched flange 14, the bracket serves the function of a hook for a pin 11 when same is slipped into either notch 15 or 16 from below the step of the flange. A central web portion 17 extends from the flange 14 to the base of the standing portion 12 of the bracket and serves to brace the flange 14. The web portion 17, lying for its major extent in the plane of the inset flange 14, also serves as a

stop and guide for directing the gudgeon pin into one or the other of the slots 15 and 16, depending upon the side from which the associative gudgeon pin is passed under the flange 14. Usually the pin is directed toward the window or door, to effect anchorage of the bottom rail 10, with the result that the outboard slot 14 of the bracket will be employed for engagement with the left hand gudgeon pin (as depicted in Fig. 1) and the slot 16 (which assumes the outboard position in the case of right side mounting) will be employed for engagement with the right hand gudgeon pin (not shown) of the blind. In both instances (right and left hand bracket installations) a central web portion 17 will serve the pin-stop and guiding function stated.

In the jamb installation of Fig. 1, the mounting may be made with a single wood screw 18 extending through the conical screw seat 19 formed in the portion 12 of the bracket. Turning of the bracket about the screw 18 is precluded by the flatwise abutment of the foot portion 13 with the sill B of the window casing. The bracket is not, however, limited to such jamb mounting but may be secured in contact solely with the sill B of the casing, as illustrated in Fig. 2. This is especially desirable where the blind is narrower than the window or other opening to be shrouded and the bracket is spaced from the jamb. In Fig. 2 the wood screw 18 is employed through the conical seat 20 of the foot portion 13 of the bracket and twisting of the bracket about the screw as an axis is precluded by a plurality of projections 21 which are embossed in the foot portion and which are caused to penetrate or otherwise key into the sill B when the screw 18 is drawn tight.

In Fig. 3 I have illustrated my bracket installed on the sill B externally of the window opening to be shrouded. Here the screw 18 is extended through the conical seat 20 as in the form of installation depicted in Fig. 2, but the standing portion 12 of the bracket is mounted outstanding from the sill. Alternatively, the bracket may be similarly disposed, but with the foot 13 screwed to the front (room) face of jamb A. In either case, the blind (not shown) is disposed in front of the door or window; not within the casing thereof. Moreover, in such instances of outside mounting, the slot 16 is normally employed for reception of the gudgeon pin at the left end of the bottom rail, and the slot 15 is normally employed for reception of the gudgeon pin at the right end of the bottom rail; it being understood that slot 15 is uppermost in the right side bracket. Blinds thus disposed external of the window or door opening are inherently longer and wider than blinds for internal installation in openings of corresponding size, and the strains imposed on the ladder tapes thereof (not shown) by reason of such greater extent, as well as by more frequent application of inadvertent external forces, may be such that stretch is usually experienced in the ladder tapes of the blind after a lesser period of service. My bracket is particularly well adapted for use with such external blinds for the reason that a second hold-down position is available through use of the pin-stop web 17 as a gudgeon-pin hold-down (illustrated by the lower, dotted-line position of the pin 11 in Fig. 3). The gudgeon-pin in the dotted-line position will, in the bracket design and size illustrated in the accompanying drawing, lie some $\frac{3}{8}$ " below that normal to use of the slots 15 or 16 as gudgeon-pin lands. Thus, a stretch of $\frac{3}{8}$ " in the ladder tapes of the associated blind (not

shown) may be readily compensated by use of the lower pin position available.

My bracket structure is an exceedingly simple one, consisting as it does of but a single piece of stamped and pressed sheet metal. It is strong, due in large part to the expanded, box-like relationship existing between the standing portion 12 proper and the bridging brace constituted by the pin stop and guide portion 11. The mode of securing the bracket upwardly or outwardly upon sill or jamb at left or right side of the blind should be clear from the several illustrations in the drawing. Functionally, the inset flange 14 with its notches 15 and 16 is a double internal hook member, but the configuration of the notch and other bracket surfaces, as well as the pin-guide web 17 militate to preclude snagging of a dust cloth or other extraneous objects thereon or therein. The gudgeon pins 11 of the bottom rail 10, conventional in Venetian blinds of current design are, however, securely held against dissociation with the slots 15 and 16 in all intended positions, as well as with the pin-guide web 17 when in the Fig. 3 dotted position. Association of the pins 11 with the brackets, upstandingly disposed as in Figs. 1 and 2, is effected simply by slightly depressing the bottom rail 10 against the tensioned support and restraint of the ladder tapes (not shown) so that the pins 11 may be moved under the inset flange 14 into abutment with the pin stop 17. Release of the bottom rail 10 will then enable the left and right hand pins 11 to enter the appropriate slot 15 and 16, and be held up therein by the elastic re-elevation of the ladder-tape suspended bottom rail 10.

Employed as an outstanding bracket, the bottom rail 10 of the blind is depressed so that its gudgeon pins bear upon the top edge of the pin stop 17, and the rail is then displaced so that the left-hand pin 11 enters the slot 16 of the left side bracket and the right-hand pin (not shown) enters the slot 15 of the right side bracket (not shown). It will be understood that in the right side bracket the slot 15 is at the top, while the slot 16 is at the bottom. Upon release of the rail 10 from depression, the ladder tapes (not shown) will re-elevate the rail so as to maintain the pins in their respective slots.

It will be apparent that the bracket may be mounted on nearly any wall portion of a building or building structure. The wall portions specifically disclosed in this connection are the front and side faces of a window jamb and the front and top faces of a window sill, these being the locations in which the bracket is most frequently mounted. However, the bracket may be similarly used in connection with a doorway, and it may be used upon a wall portion which has no opening and over which the blind is hung merely for masking or decorative effect. Where, in this specification and claims, reference is made to the "base portion" of the bracket, this expression denotes such parts of the portions 12 and 13 of the bracket as are brought into bearing upon the blind-adjacent portion of the wall in the various modes of mounting herein described.

I am aware that my invention is susceptible of embodiment in brackets of other shapes, forms and sizes than that disclosed in the accompanying drawing and herein described. I therefore claim my invention broadly, as indicated by the appended claims.

What I claim is:

1. A hold-down bracket for engagement with a bottom-rail-carried gudgeon pin of a Venetian

blind, comprising: a plate member having a base portion formed for mounting upon a blind-adjacent wall portion and having an inset flange portion provided with a notch receptive of a gudgeon pin extending outwardly from one end of the bottom rail of the blind and effective to restrain said end against swinging and flapping when said pin is so received.

2. A hold-down bracket for engagement with a bottom-rail-carried gudgeon pin of a Venetian blind, comprising: a plate member having a base portion formed for mounting upon a blind-adjacent wall portion and having a stepped flange portion cut out to define a notch receptive of a gudgeon pin extending outwardly from one end of the bottom rail of the blind and effective to restrain said end against swinging and flapping when said pin is so received.

10 3. A hold-down bracket for engagement with a bottom-rail-carried gudgeon pin of a Venetian blind, comprising: a plate member having a base portion formed for mounting upon a blind-adjacent wall portion and having a stepped flange portion cut out to define a notch receptive of a gudgeon pin extending outwardly from one end of the bottom rail of the blind and effective to restrain said end against swinging and flapping when said pin is so received.

15 4. A hold-down bracket for engagement with a correspondingly-located bottom-rail-carried gudgeon pin of a Venetian blind, comprising: a plate member having a base portion formed for mounting upon a blind-adjacent wall portion, having a double-notched inwardly-offset portion, one notch of which is receptive of the left-hand gudgeon pin and the other notch of which is receptive of the right-hand gudgeon pin when the bracket is mounted upon the wall at the left or right side, selectively, of the blind, and having a web portion between said inwardly-offset and base portions which web portion is inwardly offset with respect to said base portion and serves the dual function of bracket bracing and gudgeon-pin-guiding into the appropriate

35 notch.

5. A hold-down bracket for left or right side engagement with a correspondingly-located bottom-rail-carried gudgeon pin of a Venetian blind, comprising: a sheet metal member having a double base portion right-angularly bent for mounting either upstanding or outstanding upon the sill or jamb trim of a window or the like and having a notched portion receptive of a gudgeon pin extending outwardly from one end of the bottom rail of the blind and effective to restrain said end against swinging and flapping when said pin is so received.

40 6. A hold-down bracket for left or right side engagement with a correspondingly-located bottom-rail-carried gudgeon pin of a Venetian blind, comprising: a sheet metal member having a double base portion right-angularly bent for one screw non-rotative mounting either upstanding or outstanding upon the sill or jamb trim of a window and having an inwardly-offset notched portion receptive of a gudgeon pin extending outwardly from one end of the bottom rail of the blind and effective to restrain said end against swinging and flapping when said pin is so received.

45 7. A hold-down bracket for left or right side engagement with a correspondingly-located bottom-rail-carried gudgeon pin of a Venetian blind, comprising: a plate member having a double base portion formed for either endwise or sidewise mounting upon the sill or jamb trim of a window, having a double-notched inwardly-offset portion one notch of which is receptive of the left-hand gudgeon pin and the other notch of which is receptive of the right-hand gudgeon pin when the bracket is mounted at the left or right side respectively of the blind, and having an inwardly-offset web portion between said base portion and said notched portion merging with the latter to reinforce said bracket and to constitute a pin

stop and guide for directing said gudgeon pin into the appropriate notch of said bracket when either left or right-hand mounted.

7. A hold-down bracket for left or right side engagement with a correspondingly-located bottom-rail-carried gudgeon pin of a Venetian blind, comprising: a plate member having a base portion formed for mounting upon a blind-adjacent wall portion, having a double-notched inwardly-offset portion one notch of which is receptive of the left-hand gudgeon pin and the other notch of which is receptive of the right-hand gudgeon pin when the bracket is mounted at the left or right side, respectively, of the blind, and having an inwardly-offset web portion between said base portion and said notched portion and merging with the latter to constitute a pin stop and guide for directing said gudgeon pin into the appropriate notch of said bracket when either left or right-hand mounted, said bracket being formed from a single piece of initially flat stock punched and expanded by pressing to provide said offset portions in a box relationship resistant to collapse.

8. A hold-down bracket for Venetian blinds comprising a metal plate punched and expanded into box form with a flange at each end of the box formation, the flange at one end being formed for mounting upon the trim of a window and the flange at the other end being inwardly-offset with respect to the main portion of the bracket and having therein formed a pair of notches for the alternative reception of a gudgeon pin disposed at the left or right end respectively of the bottom rail of the Venetian blind.

9. A hold-down bracket for Venetian blinds comprising a sheet metal plate punched and expanded into box form with a flange at each end

of the box formation, the flange at one end being formed for mounting upon the trim of a window and the flange at the other end being inwardly offset with respect to the main portion of the bracket and having therein-formed a pair of non-communicating laterally-accessible notches for the alternative reception of a gudgeon pin disposed at the left or right end, respectively, of the bottom rail of the Venetian blind.

10. 10. A hold-down bracket for one end of the bottom rail of a Venetian blind, comprising: a sheet metal plate punched and expanded into box form with a flange at each end of the box formation, the flange at one end of the box formation being formed for outstanding mounting upon a blind-adjacent wall portion and the flange at the other end of the box formation lying in a plane inward of the main portion of the bracket and having a notch therein, said notch and a wall of said box formation being alternatively engageable with a gudgeon pin carried by one end of the bottom rail of the blind, and serving to restrain movement of said bottom rail at either of two levels.
11. 11. A hold-down bracket structure for restraining a gudgeon-pinned bottom rail of a Venetian blind against undesirable movement comprising: a punched sheet metal plate having a rotation-resisting wall-attachable flange portion for one-screw mounting upon either a vertical or a horizontal surface such as offered by a window jamb or sill, and a blind-securing portion having a plurality of gudgeon-pin-receptive recesses selectively effective to suppress said bottom rail to a desired one of a number of optional positions having distinct vertical levels relative to the point of mounting of said bracket.

HARRY H. NELSON.
